UNITED STATES PATENT OFFICE.

HERBERT ETHERIDGE, OF EALING, LONDON, ENGLAND, ASSIGNOR TO THE BAR-LOCK
TYPEWRITER COMPANY LIMITED, OF LONDON, ENGLAND.

TABULATOR MECHANISM FOR TYPE-WRITERS.

1,200,328.

Specification of Letters Patent.

Patented Oct. 3, 1916.

Application filed March 22, 1916. Serial No. 85,805.

To all whom it may concern:

Be it known that I, HERBERT ETHERIDGE, a subject of the King of England, residing at Ealing, London, W., England, have invented 5 certain new and useful Improvements in Tabulator Mechanism for Type-Writers, of which the following is a specification.

This invention is for improvements in or relating to tabulator mechanism for type-writers and has for its object to provide a modified form of the type of tabulator mechanism wherein a single dog is advanced different heights to engage one or other of a series of stops on the platen carriage, which 15 stops are graded in length, and a stepped member is provided which is adjusted according to the column in which writing is to occur, the said stepped member being advanced by the tabulator-dog to release the 20 platen-carriage when the dog has been brought into position for engaging its stop. A single dog is used to engage any one of the stops for each key, but obviously several 25 keys may be provided each with its own dog to operate, for example, as denominator-keys.

The present invention relates to the specific form of mechanism whereby the stepped member is carried, made adjustable, and is 30 operatively connected with the tabulator-dog and its key.

In the accompanying drawing which illustrates one method of carrying out this invention, the adjustable stops ordinarily provided at the back of the typewriter carriage for tabulator mechanisms are shown at A, A¹, A² and A³ respectively, the length of 35 the stops increasing in the order in which they are named. As is well-known these 40 stops are commonly carried on a bar A⁴ secured to the back of the carriage and along which they are free to slide, and made to engage with a second bar A⁵ which is provided with a series of notches A⁶, which 45 notches engage the upper part of each stop. The notches correspond to the writing positions of the type and any one stop can be slid to any one position along the bar by raising it to free it from its notch A⁶ and 50 then sliding it along to engage it with another notch. With the stops arranged so that the shortest one is at the left-hand of the operator and the longest at the right-hand, the carriage can be arrested at any 55 desired position by raising the tabulator-dog

B to such height as to lie in the path of that stop which is so placed as to arrest the movement of the carriage as soon as the desired position is reached. All this mechanism is well-known and constitutes no part 60 *per se* of the present invention. With such mechanisms, however, the carriage, which has to be released by some part which moves with the tabulator-dog, is commonly released just as the dog arrives about at 65 the lower edge of the stop with which it is to coöperate, so that it is likely to catch the stop by the extreme edge, or even miss it altogether. To overcome this objection, the present mechanism is arranged so that the 70 carriage-release only takes place after the tabulator-dog B has been brought well up above the lower edge of the stop with which it is to engage. The tabulator-dog B is carried at the end of a vertical rod B¹ which is 75 slotted at B² to engage a guide-rod B³. The lower end of the rod B¹ is pivotally engaged with a key-lever C which rocks upon a fixed support C¹ and is normally held in such position by a spring C² that the end 80 engaging the rod B¹ is lowered and the other end which carries the key C³ is raised. The rod B¹ has a laterally-projecting tongue B⁴ which lies under one end of a rocking-lever D, pivoted on a support D¹. 85

A lost-motion device D², which constitutes a selector, is pivoted at D³ to that end of the lever D which is remote from the tongue B⁴. The selector is in the form of a link having four steps, d, d¹, d² and d³. A bell- 90 crank lever E constituting an escapement release member is pivoted at E¹ and on one of its arms carries a pin E² which lies vertically beneath one or other of the steps d, d¹, d², d³ according to the position in which the selector is placed. For positioning the selector, a bell-crank lever F is provided which is situated in some part of the machine 95 easily accessible by the operator and this is connected by a wire link F¹ to the selector. 100 The bell-crank lever F can be moved over a scale F² marked to indicate four different positions, and means are provided, such as a spring detent, not shown in the drawing, for holding the lever F in any one position 105 in which the operator may set it. When the lever is set at the "4" as shown in the drawing, the step d³ is vertically over the pin E². Near one arm of the bell-crank lever, one 110 end of a member G is shown which is opera-

tively connected with the escapement-dogs for releasing the platen-carriage.

The operation of this mechanism is as follows:—If with the parts in the position shown in the drawing, the key C³ is depressed to the limit of its movement, the rod B¹ will be raised so that the tabulator-dog B is lifted until its top edge rises above the bottom edge of the stop A. During this movement the tongue B⁴ on the rod B¹ has been rocking the lever D so that the selector D² is lowered, and as the step d³ lies opposite the pin E² the selector will move downward without displacing the lever E until the step d³ comes into contact with the pin E². By this time the tabulator-dog B is well up in front of the stop A, and further movement of the tabulator-dog and consequently of the selector D² then displaces the lever E which swings the member G backward and releases the escapement-dogs. The carriage then shoots forward in the known manner until the first stop A is brought against the tabulator-dog B when the operator releases the key C³, and the escapement-dogs being reengaged, the carriage remains in the position in which it was arrested. The step d³ allows the greatest lost-motion travel of the selector D² because the tabulator-dog B has to be raised to the full limit of its travel to engage the stop A, but if the hand-operated lever F is placed at one of the other points on the index, say that numbered "2", the step d¹ will be brought over the pin E² and thus the selector will travel a shorter distance before releasing the escapement-dogs, as the tabulator-dog has only to rise sufficiently high to engage the stop A².

40 The lever E, in addition to effecting the release of the escapement-dogs, serves as a stop for the selector and its associated parts. For this purpose the rearward movement of the member G can be limited, so that the lever E can only swing clockwise a given distance, and then being checked by the member G butting against its stop, holds up the selector D² and the lever D, and thus prevents further upward movement of the rod B¹ with the dog B, and further downward movement of the key C³. It will be seen therefore that the lever E is always rocked through the same angle, but the lever D is rocked through a greater or smaller angle 55 according to the positioning of the selector D², and thus the degree of lost-motion permitted to it; it is this difference of lost-motion which permits the dog B to be raised to varying points according to the stop selected to be engaged by the index over which the hand-operated lever F is moved. The member G would be spring-controlled and thus the lever E would be returned by this member when the key is released. The 60 lever has a forwardly-extending tongue E³

which is bent over at right-angles to engage the link F¹ or any other member which may serve as a stop to limit the movement of the lever in a counter-clockwise direction. The key with the tabulator-dog is returned by the spring C²; the lever D may be returned by a spring not shown in the drawing.

Usually the operator is working only in one column, or mainly in one column, and by being able to set the selector over to this column by means of the lever F and leave it in that position, time is saved over such mechanisms as necessitate the operating of a special key for each column. Another advantage of this mechanism is, that once the selector D² is set, any one of the decimal keys with their respective dogs, such as are usually employed in conjunction with column keys and column dogs, can be operated without having to first or simultaneously operate a column key, as the selector decides which column the decimal key is for the time being allotted to; all of these decimal keys would of course have dogs with projections corresponding to B⁴ operating on the same bail-lever D.

What I claim as my invention and desire to secure by Letters Patent is:—

1. In tabulator-mechanism for typewriters and the like, the combination of a series of dependent stops on the carriage which is to be moved to the different tabulating positions, said stops being graduated in length downward, a vertical-member having a tabulator-dog at the top and mounted to move vertically to bring the dog into the path of the stops, a horizontally-disposed key-lever pivotally connected to the bottom of the tabulator-dog member at that end which is remote from the key, a bail-lever (D) pivoted about a horizontal axis and having the bail end disposed over a projection (B⁴) on the tabulator-dog member, a selector movably mounted on the bail-lever at that end remote from the bail and having a stepped face, a carriage-release member opposed to the stepped face of the selector and operatively connected with the release-mechanism for the carriage whereon the stops are mounted, and means for adjusting the selector by moving it on the bail-member so that any one of its steps can be brought opposite the end of the carriage release member as desired, the steps being so arranged that each when brought to its operative position lies a distance from the end of the releasing member which is greater or less than the other steps; substantially as and for the purpose set forth.

2. In tabulator-mechanism for typewriters and the like, the combination of a series of dependent stops on the carriage which is to be moved to the different tabulating positions said stops being graduated in length downward, a vertical member having a

tabulator-dog at the top and mounted to move vertically to bring the dog into the path of the stops, a horizontally-disposed key-lever pivotally connected to the bottom 5 of the tabulator-dog member at that end which is remote from the key, a bail-lever (D) pivoted about a horizontal axis and having the bail end disposed over a projection (B⁴) on the tabulator-dog member, a 10 stepped plate (D²) pivotally carried at that end of the bail-lever remote from the bail, a movable member (E) whose end lies in the path of one of the steps of the said plate, means for swinging the plate on its lever 15 and holding it in such position that any one

of its steps can be brought opposite the end of the carriage-release member as desired, the steps being so arranged that each when brought to its operative position lies a distance from the end of the releasing-member 20 which is greater or less than the other steps; substantially as and for the purpose set forth.

In testimony whereof I have signed my name to this specification in the presence of 25 two subscribing witnesses.

HERBERT ETHERIDGE.
